Attorney

UNITED STATES PATENT OFFICE.

WILLIAM R. K. GANDELL, OF LONDON, ENGLAND.

HOLDER FOR STRIPS OF EMERY, CARBORUNDUM, GLASS-COVERED TAPES, CLOTH, OR PAPER.

Application filed January 28, 1922. Serial No. 532,506.

To all whom it may concern:

Be it known that I, WILLIAM RALEIGH KERR GANDELL, a subject of the King of Great Britain, residing in London, England, have invented certain new and useful Improvements in Holders for Strips of Emery, Carborundum, Glass-Covered Tapes, Cloth, or Paper, of which the following is a specification.

10 My invention relates to improvements in holders for strips of paper, cloth or like material covered with emery or other abrasive or an absorbent substance, the holders being of the kind that comprise a bar for operatively supporting a strip, means adjustably mounted on the bar for gripping the strip to the bar and said means being capable of being shifted longitudinally of the bar for the purpose of making the strip thereon 20 taut.

The object of the invention is to produce a holder of the above kind which is more simple and cheaper to manufacture than has been the case hitherto. According to the invention a strip of abrasive or absorbent material is retained in operative position on the supporting bar by the instrumentality of a gripping device, consisting of a slidably mounted sleeve encompassing the strip and bar in such a manner that, when one or other part of the gripping device is held and a blow is imparted to end of the bar or the latter be pushed in a direction longitudinally thereof, a relative longitudinal movement between the bar and the gripping device or a part thereof will occur which will tend to render the strip taut. A relative movement may also take place between the parts of the gripping device.

40 The invention will be described with reference to the accompanying drawings, in which different forms of the improved holder are illustrated.

Fig. 1 in the drawings is a side elevation of the holder in one of its simplest forms.

Fig. 2 is an elevation representing a modified arrangement of the holder and gripping device.

Fig. 3 is a side elevation of a metal supporting bar that is bent between its ends to permit one external face of the sleeve to be flush with or recessed with respect to that

portion of the face of the supporting bar to which the strip is applied.

Fig. 4 is a side elevation of a supporting bar for use in carpentry work.

Fig. 5 is an end view of a split sleeve, and Fig. 6 is a side elevation of a strip supporting bar, constructed similarly to that in Fig. 1, but with the sleeve and wedge of the gripping device assembled on the holder in a reverse direction.

Fig. 7 is a longitudinal section of the end portion of a supporting bar remote from its handle, and illustrates a modification.

In the several figures, corresponding parts are denoted by the same reference letters.

In Fig. 1, *a* denotes a straight bar or support, which is preferably of metal, but may be of wood or other appropriate material, and of rectangular or other convenient cross section. One end of the supporting bar *a* may be suitably shaped to form a handle or have a handle grip *a'* fitted to it. A strip of emery paper or cloth is indicated by the reference letter *b*. The strip, which may be of any convenient length, is doubled at the centre of its length, or thereabouts, and is arranged to overlie the top and bottom faces of the bar *a* and pass round the end 80 thereof remote from the handle. The two ends of the strip pass through a suitably shaped sleeve piece *c*, which is slidably mounted on the bar *a* and can be adjusted to any position along the length of the supporting bar and be there retained, in a manner to grip the strip against the bar, by means of a wedge piece *d*, which is here shown with its thin edge directed away from the handle end of the bar, the wedge being shaped to 90 co-operate with both the sleeve and the bar.

In order to make the strip taut when the parts are thus assembled, the sleeve is held stationary and a blow or a push is imparted to the handle end of the supporting bar to cause a slight relative movement between the parts, thereby stretching the strip. For the better holding of the sleeve this may be provided with wings or projections *j*.

When the sleeve and wedge are assembled on the bar as in Fig. 6, that is to say, with the wedge pointing in a direction reverse to that shown in Fig. 1, then, in such case, in order to make the strip taut, the wedge and

not the sleeve is held while a blow is imparted to the handle end.

The wedge piece d' in Fig. 2, is shown as extending rearwardly and shaped to constitute a hand grip in place of the separate hand grip a' , as shown in Fig. 1.

It is more economical to use a strip of sufficient length to cover the greater portion of the top and bottom faces of the support, 10 but if a strip of such length be not available, then instead of the strip overlying two faces of the supporting bar, it may be arranged to overlie one face only, one end of the strip being gripped by the sleeve c while 15 the other end may be inserted in a V shaped groove h provided for the purpose in the end of the bar a and be wedged therein by means of a wedge piece i as indicated in Fig. 7.

20 Alternatively, the sleeve may be a split one, as shown in Fig. 5.

When the bar a is of metal the bar may be bent between its ends, as shown for example in Fig. 3, to allow the one face of the 25 sleeve applied to the portion of the bar nearer the handle end to be flush with the face of the portion of the bar further from the handle.

The support for the abrasive or absorbent strip may be formed as shown in Fig. 4 without a handle portion, for use in carpentry operations. In this case the bar would be made considerably wider and of greater depth than in the examples described above, and a pad k of felt or other appropriate material may be interposed between the bar and the strip b . One end of the supporting bar a would be reduced in thickness, and also, if desired, in width, to 40 accommodate the sleeve and associated gripping means.

Having thus described the nature of the

said invention and the best means I know of carrying the same into practical effect, I claim:—

45 1. An abrasive or absorbent strip holder of the character specified, comprising in combination a bar forming a support for a strip folded transversely near the center of its length over one end of the bar, a sleeve member having a tapering bore and adapted to be slid along the bar, said sleeve member being arranged to encompass the bar and the two ends of the strip at opposite sides of the bar, and a correspondingly tapered wedge member inserted within said bore and capable of longitudinal sliding movement relatively to the sleeve member for the purpose of clamping the ends of the strip to the bar, one of said members 50 being manually adjustable with respect to the bar to render the strip taut.

2. An abrasive or absorbent strip holder of the character specified, comprising in combination a bar having a recessed part 55 and forming a support for a strip folded transversely near the center of its length over one end of the bar, a sleeve piece having a tapering bore and adapted to be slid along the bar, said sleeve piece being arranged to encompass the recessed part of the bar and the two ends of the strip located at opposite sides of the bar, and a correspondingly tapered wedge inserted within said bore and capable of a longitudinal 60 sliding movement with relation to the sleeve for the purpose of securing the said ends of the strip to the bar, the said sleeve piece and wedge being manually adjustable as a whole with respect to the bar to render the 65 strip taut.

70 In testimony whereof I have signed my name to this specification.

75 WILLIAM R. K. GANDELL.
